Inventor.

Col. E. F. Plyes.

UNITED STATES PATENT OFFICE.

EMANUEL J. PLEYEL, OF DALLAS COUNTY, IOWA, ASSIGNOR TO HIMSELF AND ALBERT ZEIGELE, OF BUFFALO, NEW YORK.

IMPROVED HORSESHOE.

Specification forming part of Letters Patent No. 40,215, dated October 6, 1863.

To all whom it may concern:

Be it known that I, EMANUEL J. PLEYEL, of the county of Dallas and State of Iowa, have invented new and useful Improvements in Horseshoes; and I do hereby declare that the following is a full and exact description thereof, reference being had to the accompanying drawings, and to the letters of reference marked thereon, making a part of this specification.

The nature of my invention consists in the shape and construction of six-sided calks with their double-shouldered screws.

To enable others skilled in the art to make and use my invention, I describe its construction as follows:

Figure 1 represents the horseshoe; Fig. 2, a side view of the horseshoe; Fig. 3, the movable toe-piece; Fig. 4, the movable six-sided and pointed calk; Fig. 6, a top view of Fig. 4; Fig. 6, the movable flat-headed and six-sided calk.

A represents the ordinary grooves in the horseshoe, in which are apertures B, for the purpose of fastening the shoe to a horse's foot by nails, as usual.

C represents the front part or toe of shoe, raised about one-fourth of an inch and flat at top, upon which the toe-piece D is fitted, and fastened to the shoe by screws. The toe-piece D, as shown at Fig. 3, exhibits the main screw E, which holds it permanently to the shoe. The screw E is located in the center of the toe-piece D, with the double shoulders, the upper shoulder, G, to strengthen the screw E, and the lower shoulder, H, at the bottom of the screw E, to likewise strengthen and hold firmly the toe-piece D to the shoe, the screw E, having a straight point, I, extending from the

lower shoulder, H, to the face of the shoe, to assist in maintaining the permanency of the toe-piece D. The shoe has its aperture J and female screw to correspond with the screw E, being countersunk at top of the female screw, and straight below the screw, as shown in dotted lines at Fig. 2. The toe-piece D, as shown at Fig. 1, is flatter and blunter at the point for summer use than the sharper-edged toe-piece D, as shown at Fig. 3, for winter use, and they are also fastened to the shoe by side screws, K, to brace the main screw E and prevent any possibility of its loosening.

L, at Fig. 6, represents the flat six-sided calk for summer use, with its similar screw, E, which is screwed firmly into the heel M of the shoe, into its corresponding aperture J, and female screw.

N, Fig. 4, represents the pointed six-sided calk for winter use, having its like screw E, which is also screwed firmly into the heel M of the shoe, into its corresponding apertures, J, and female screw.

The advantages are the changing of the toe pieces and calks in the most expeditious manner according to the roads in pleasant or icy weather, and maintaining their permanent positions in the shoe by the double-shouldered screws.

What I claim as my invention, and desire to secure by Letters Patent, is—

The six-sided calks L and N, with their double-shouldered screws E, constructed and combined as herein described, and for the purposes set forth.

E. J. PLEYEL.
